Harrison H. Boyce INVENTOR

BY

James Quincy Moore ATTORNEY

UNITED STATES PATENT OFFICE.

HARRISON HURLBERT BOYCE, OF FOREST HILLS, NEW YORK.

DESIGN FOR A COMBINED MOTOR-VEHICLE RADIATOR-CAP AND TEMPERATURE-INDICATING INSTRUMENT.

55,502.

Specification for Design. Patented June 22, 1920.

Application filed March 15, 1920. Serial No. 366,120. Term of patent 14 years.

To all whom it may concern:

Be it known that I, HARRISON H. BOYCE, a citizen of the United States, residing in Forest Hills, county of Queens, and State of New York, have invented a new, original, and ornamental Design for a Combined Motor - Vehicle Radiator - Cap and Temperature - Indicating Instrument, of which the following is a specification, reference being had to the accompanying drawings, forming a part thereof.

Figure 1 is a front elevation of a construction embodying my invention;

Fig. 2 is a plan view thereof.

What I claim is:

The ornamental design for a combined motor vehicle radiator cap and temperature indicating instrument, as shown.

HARRISON HURLBERT BOYCE.
